J. I. ROBIN.

GAS HEATER.

APPLICATION FILED DEC. 11, 1919.

1,351,004.

Patented Aug. 24, 1920.

By his Attorney
Jacob I. Robin Inventor
Max F. Dromauer

UNITED STATES PATENT OFFICE.

JACOB I. ROBIN, OF NEW YORK, N. Y.

GAS-HEATER.

1,351,004.

Specification of Letters Patent. Patented Aug. 24, 1920.

Application filed December 11, 1919. Serial No. 344,078.

To all whom it may concern:

Be it known that I, JACOB I. ROBIN, a citizen of the United States of America, residing at New York, in the county of New York and State of New York, have invented certain new and useful Improvements in Gas-Heaters, of which the following is a specification.

This invention has reference to heaters for artificial, natural, or vapor gas and in which the flame is produced by the aid of a bunsen and has as its principal object to produce a heater of simple and durable construction and whereby, with a comparatively small amount of fuel, a powerful heating flame can be produced.

To accomplish my object, I provide a heater in which the heat is directed downwardly by a heat bell, the bottom or mouth of which is obstructed by a perforated surface of heat conducting material, arranged in a plane where it will intersect the currents of gas mixture, whereby a perfect combustion of the latter will be caused to take place at the bottom or mouth of the bell and an exceedingly strong blue flame will be produced on the outside of the perforated surface.

My invention is based on the fact that when, in a current of gas mixture, a finely perforated surface is introduced, this surface will minutely divide this mixture and permit the secondary air to become thoroughly mixed with it so that a more complete combustion of the mixture is effected at the outer layer of the flames. By making the perforated surface of heat conducting material such as wire gauze, the heat radiated therefrom will additionally aid in producing a complete combustion.

The perforated surface additionally acts as a safety means against the escape of gas into the room, when the flame or flames are accidentally blown out. In such case, the currents of the gas mixture continuing to issue from the jet openings will be immediately reignited at the said openings by the heat radiating from the perforated surface.

My invention also consists in the particular construction, combination and arrangement of parts as will hereinafter be more fully described and defined in the appended claims.

In the accompanying drawing in which

similar reference characters denote corresponding parts, Figure 1 is a vertical sectional elevation of my new heater; Fig. 2 is a reduced cross section on line 2—2 of Fig. 1, as seen in the direction of the arrows; Fig. 3 is a cross section on line 3—3 of Fig. 1; Fig. 4 is a vertical section of a part of the bell with a modified construction of the obstructing member at the bottom thereof; Fig. 5 is a bottom view thereof, and Fig. 6 is a top plan view of an incandescent body and holder to be applied to the burner tube.

Referring to the drawing more in detail, *a* denotes an ordinary bunsen on which is mounted a burner or mixing tube *b* carrying at its upper end a conical fitting or manifold *c* which is provided with a plurality of burner openings *c'* and a shell or bell *d* which may be or may not be of heat conducting material, mounted centrally on top of the said fitting *c* to inclose a comparatively large space around the flames.

Attached to the bell or otherwise fixed in position is a perforated member *e* in form of a wire gauze, preferably of copper, which is adapted to partially obstruct the open bottom or mouth of the bell and to lie in a plane intersecting the currents of the gas mixture issuing from the burner holes.

According to the present embodiment of my invention, I provide to this end two concentric rings *f*, *f'* which may be made of refractory or other suitable material and of which the inner ring *f* is made to fit on the mixing tube *b* and the outer ring *f'* may be provided with projections *f''* adapted to be bent around the circumferential bottom edge of the bell and to serve as retaining means. The gauze is stretched over the two concentric rings and suitably fastened thereto. The outer ring *f'* may be made of somewhat smaller diameter than the diameter of the outer edge of the bell so that a substantially unobstructed annular space *g* will be left between the latter and the said ring *f'*.

By reason of the gauze dividing minutely the gas mixture striking it in its downward flow, the secondary air rushing in from the outside through the openings adjacent to the currents of gas mixture will become thoroughly mixed with said mixture and thereby complete the combustion at the outer layers of the flames through which extends the perforated surface. The completion of

the combustion will be additionally aided by the heat radiated into the mixture from the heated wire gauze. As a result of this, a powerful blue flame is produced spreading along the entire outer surface of the wire gauze. At the same time, the inrushing secondary air will deflect the flame against the bell body causing it to issue through the annular opening *g*.

- 10 To convert the blue flame in a red glow I may provide in the annular space *g* a netting *h* of refractory and non-combustible material *g'*, such as asbestos, clay or the like. Such netting is shown in Figs. 4 and 15 5. The netting may be in form of a single piece stamped of a sheet of asbestos or the like, or may be formed from asbestos threads covering the annular space *g* in zig-zag form.
- 20 In the example shown, the top of the bell is adapted to serve as a cover for the manifold *c* and to this end is hollowed to form a cap *d'* with an annular groove *d* therein adapted to engage the upper outwardly bent edge of the conical manifold *c*. The 25 central part of the cap *d'* is pressed downwardly in form of a cone *d* the point of which extends toward the center of the mixing tube and which serves to aid in bringing about a uniform distribution of the gas mixture entering the manifold from the mixing tube.

Without in any way affecting the heat capacity of my heater the bulb shaped parts 35 of the flames, projecting downwardly from the wire gauze where the latter intersect, the currents of the gas mixture may be utilized for illuminating purposes. To this end incandescent bodies such as a sheet or 40 sheets of impregnated mantle fabric may be suitably suspended from the heater to extend though the said bulb shaped portions of the flame. In the present example a holder *i* in form of a fork is provided which 45 may be suitably supported on the mixing tube. The incandescent body *j* may consist of a piece of mantle fabric to the longitudinal edges of which may be fixed tubular 50 sockets *k* capable of engaging the arms of the forked holder, so that the body *j* may be slipped over and supported by the forks.

Since this construction and that of my heater may be modified in various ways without departing from the spirit of my invention, I do not wish to limit myself to the details described and shown.

What I claim and desire to secure by Letters Patent is:—

1. In a gas heater, the combination with a 60 bunsen, of a manifold burner having downwardly directed jet openings, a bell, and a perforated surface extending substantially through the entire area of the mouth of said bell and adapted to intersect the gas currents, so as to cause complete combustion of

the gas mixture and produce thereby blue flames on the outer face of said perforated surface.

2. In a gas heater, the combination with a bunsen, of a manifold burner, a bell supported on said burner and a perforated surface of heat conducting material, extending substantially over the entire mouth of said bell in a plane intersecting the currents of the gas mixture and suspended from said bell, whereby a complete combustion of the mixture will take place on the outer face of said perforated surface and blue flames produced.

3. A gas heater, comprising a bunsen, a mixing tube thereon having a plurality of burner openings, a heat bell adapted to envelop the currents of the gas mixture issuing from the burner openings, and a perforated surface of heat conducting material stretched across the mouth of and secured to said bell to intersect said currents and to form an annular opening between itself and the bell body, for the purpose specified.

4. A gas heater comprising a bunsen, a mixing tube thereon, a manifold on said mixing tube having a plurality of burner openings, a bell mounted on said manifold and adapted to envelop the currents of the gas mixture issuing from said burner openings and a wire gauze supported from said bell to extend substantially over the entire mouth of said bell in a plane intersecting said currents and to leave an annular opening between itself and the bell for the purpose specified.

5. A gas heater comprising a multiple Bunsen burner, a heat bell supported thereon and adapted to envelop the currents of gas mixture issuing from said burner, a wire gauze suspended from said bell to extend substantially over the entire mouth of said bell in a plane intersecting the currents of the gas mixture and to leave an annular opening between itself and said bell and a perforated body of refractory material obstructing said opening for the purpose specified.

6. In combination with a gas heater as per claims 1-5 of an illuminating device consisting of a holder supported on the burner tube and an incandescent body suspended from said holder.

7. In combination with a gas heater as per claims 1-5, of an illuminating device consisting of a forked holder supported on the burner tube, and an incandescent body supported on said holder.

8. In a gas heater, a bunsen, an upright mixing tube, a manifold on the upper end of said mixing tube having a plurality of downwardly directed openings, a bell supported on said manifold and a perforated surface of heat conducting material extending substantially over the entire area of the

mouth of said bell and suspended from said bell, said perforated surface being adapted to cause complete combustion of the gas mixture flowing therethrough and to produce blue flames on its outer face.

9. In a gas heater, a bunsen, an upright mixing tube leading from said bunsen, a manifold supported on top of said mixing tube and having a plurality of downwardly directed jet openings, a bell supported on top of said manifold and a disk shaped perforated surface extending substantially over the entire area of the mouth of said bell and suspended from the latter, said perforated surface being adapted to cause complete combustion of the gas mixture and produce blue flames on its outer face.

10. In a gas heater, a bunsen, an upright mixing tube leading from said bunsen, a manifold supported on top of said mixing tube and having a plurality of downwardly directed jet openings, a bell supported on top of said manifold and a disk shaped member extending over the mouth of said bell and composed of annular concentric rings and a gauze stretched over the annular face between said rings, the said gauze being adapted to intersect the gas currents to cause complete combustion of the gas mixture and produce blue flames on its outer face.

11. In a gas heater, a bunsen, an upright mixing tube leading from said bunsen, a manifold supported on top of said mixing tube and having a plurality of downwardly directed jet openings, a bell supported on top of said manifold and a disk shaped member composed of two concentric rings, the outer ring having arms engaging said bell and the inner ring being mounted on said mixing tube and a gauze stretched over the annular space between said two rings and fixed to the latter, said gauze being adapted

to intersect the gas currents and thereby effect complete combustion of the gas mixture and produce blue flames on its outer face. 45

12. In a gas heater, a bunsen, an upright mixing tube leading from said bunsen, a manifold supported on top of said mixing tube and having a plurality of downwardly directed jet openings, a bell supported on top of said manifold and a disk shaped member extending over the mouth of said bell, said member being composed of two concentric rings, of which the outer one is smaller in diameter than the diameter of 55 the mouth of said bell to form an annular space between itself and said bell and has arms engaging the latter and of which the inner ring is mounted on said mixing tube and a gauze stretched over the annular space 60 between said two rings and connected to the latter, the said gauze being adapted to intersect the gas currents to effect complete combustion of the gas mixture and produce blue flames on its outer face. 65

13. A combination gas heater and lamp consisting of a bunsen, a mixing tube leading from said bunsen, a manifold on said mixing tube having a plurality of downwardly directed jet openings, a bell supported on said manifold, a perforated surface extending substantially over the entire area of the mouth of said bell to cause complete combustion of the gas mixture and produce blue flames on its outer face and a 70 holder mounted on said mixing tube to intersect the flames and serving to support incandescent bodies. 75

In testimony whereof I affix my signature in presence of two witnesses.

JACOB I. ROBIN.
